UNITED STATES PATENT OFFICE.

WILLIAM E. KEMP, OF NEW YORK, N. Y.

RECORDING INSTRUMENT FOR VEHICLES.

1,255,758.

Specification of Letters Patent.

Patented Feb. 5, 1918.

Application filed June 9, 1915. Serial No. 33,123.

To all whom it may concern:

Be it known that I, WILLIAM E. KEMP, a citizen of the United States, and a resident of the city of New York, in the county 5 of New York and State of New York, have invented certain new and useful Improvements in Recording Instruments for Vehicles, of which the following is a specification.

10 The present invention relates to recording instruments for vehicles.

In these times of efficiency engineering, it has been found desirable to produce permanent records of vehicle performances. As 15 long as the record relates to passenger carrying vehicles, for instance automobiles, a simple speed recording instrument is sufficient, the latter recording not only the speed of the travel and the distances traveled, but 20 also the time consumed in stoppages, indicating clearly the working time of the driver of the vehicle, the number of miles the vehicle has traveled, and the rate of speed at which the vehicle has been driven. As soon 25 as, however, the performance record of a truck, for instance of a motor truck, has to be taken, another element enters into consideration, to wit: the load carried by the vehicle, and naturally the time consumed in 30 loading and unloading.

The use of speed recording instruments on motor vehicles is old and well known. Such instruments comprise usually a clock work driven record tape carrier, in combination 35 with a marker that is actuated by one of the wheels of the vehicle, thereby producing in the well known manner a record of the speed, distance and stoppages of the vehicle. It has also been proposed heretofore to provide 40 trucks, such as motor trucks, with a weighing mechanism and mileage recorder, such instrument including a record sheet, in combination with a marking device that is actuated by the depression of the vehicle body under the weight of the load, combined with a mechanism that is operated by 45 one of the carrying wheels of the vehicle for moving said sheet to indicate thereon the distance the vehicle has traveled. If both 50 of these devices were mounted on the same vehicle, two independent records would be obtained, one record tape being actuated by a clock mechanism and the other tape by one of the vehicle wheels. These two rec-

ords could, therefore, not be read conjointly, 55 there being no relation therebetween.

It is now one of the objects of the present invention to bring the speed, distance and stoppage record of a vehicle in such relation to its load record that they can be read together, thereby securing a record indicating the following data:

1. The time at which the vehicle is started in motion, and the periods of time during which it is in motion. 65

2. The point or points of time at which the moving vehicle comes to a stop, and the time during which the stop continues.

3. The speed of travel, and also the changes of speed. 70

4. The distance traveled by the vehicle.

5. The weight of the load carried by the vehicle in relation to time and distance, and

6. The time consumed in loading, unloading, or partially unloading the vehicle. 75

With these and other objects in view, which will more fully appear as the nature of the invention is better understood, the same consists in the combination, arrangement and construction of parts hereinafter 80 fully described, pointed out in the appended claims and illustrated in the accompanying drawings, it being understood that many changes may be made in the size and proportion of the several parts and details of 85 construction within the scope of the appended claims without departing from the spirit or sacrificing any of the advantages of the invention.

Two of the many possible embodiments of 90 the invention are illustrated in the accompanying drawings, in which:—

Figure 1 is a longitudinal vertical section taken through a portion of a motor truck with the recording instrument, forming the 95 subject matter of the present application for Letters Patent, mounted thereon; Fig. 2 is a plan view of a portion thereof; Fig. 3 is a front elevation of the recording instrument; Fig. 4 is a section taken on line 100 4—4 of Fig. 3; Fig. 5 is a section taken on line 5—5 of Fig. 3; Fig. 6 is a section taken on line 6—6 of Fig. 3; Fig. 7 is a section taken through a detail of one of the marking devices of the instrument; Fig. 8 is a 105 section taken on line 8—8 of Fig. 7; Fig. 9 is a section taken through the record tape carrier; Fig. 10 is a section taken on line

10—10 of Fig. 9; Fig. 11 is a section taken through the tensioning device of the record tape carrier; Fig. 12 is a section taken on line 12—12 of Fig. 11; Fig. 13 is a section 5 taken through the actuating device of the arm carrying one of the marking devices; Fig. 14 is a section taken through the actuating device of the arm carrying the other marker; Fig. 15 is a plan view of a detail 10 of the load recording mechanism with its cover removed, in order to more clearly show the interior construction; Fig. 16 is a section taken on line 16—16 of Fig. 15; Fig. 17 is a section taken on line 17—17 of Fig. 15; Fig. 18 is a section taken through a portion 15 of a vehicle wheel and the mechanism connected therewith for operating the marker producing the speed, distance and stoppage record; Fig. 19 is a section taken 20 on line 19—19 of Fig. 18; Fig. 20 is a view of a portion of the record tape showing two diagrams made by the two markers; Fig. 21 is a view of a modified record tape; and Fig. 22 is a plan view of a motor truck having a modification of the invention mounted 25 thereon.

Broadly speaking, the invention consists 30 of a record tape carrier operated by a clock mechanism and coöperating with two markers, one of which is actuated by one of the wheels of the vehicle, and the other one by the depression of the vehicle body under the weight of the load thereon.

Before going into the details of the recording mechanism, the record tape shown 35 in Fig. 20 of the drawings will be described. This tape is denoted by the numeral 30, and is provided with divisions which are formed by transverse and longitudinal lines. The 40 transverse lines 31 divide the tape into fractions of the hour, and the longitudinal lines 32 into fractions of a mile. In the case illustrated in the drawings the fractions of the hour are to indicate fifteen minutes, and the fractions of a mile are to indicate one-quarter. Each fifth line 31, representing an 45 hourly division line, is drawn somewhat heavier than the other lines, and associated therewith is an indication 33. Transversely 50 the tape is shown as indicating two miles, each divided fractionally, the miles being divided by a heavy line 34. The longitudinal division lines are furthermore provided, as at 35, with indications running from "0" 55 to "160." The indications denote, as will hereinafter appear, load, percentage, the fraction between two longitudinal lines representing 20%.

The recording instrument comprises a 60 casing 36, which is attached to a stationary part of a truck 37, for instance to its dash board 38, said casing being provided with a cover 39, hinged thereto at 40. Within the casing is disposed a clock train or motor mechanism 41, to which is geared the

record tape carrying device, the latter comprising a drum 42, which coöperates with a supply reel 43 and a wind-up reel 44. The drum 42 is loosely mounted upon a spindle 45, that is fixedly attached to the base plate 70 of the casing, said drum being held in place, for instance, by a cotter pin 46, passing through said spindle and holding at the same time on the latter a blade spring 47 for a purpose presently to be described. Upon 75 the drum is formed a spur gear 48, meshing with a gear 49 of the clock train, whereby rotation is imparted to the drum. The record tape is wound upon the supply reel 43, and passes around a portion of the drum 80 42 to the wind-up reel 44, to which it is secured. The supply and wind-up reels are alike in construction, each of the same being provided with a tapered seat 50, bearing against conical portions 51 of their supporting spindles. The spindle 52 of the supply reel is rotatably mounted on a lever 53, pivoted at 53' to the base plate of the casing 36, while the supporting spindle 54 of the wind-up reel 44 is rotatably mounted in 90 the said base plate. The spring 47 above-mentioned bears against the two reels, forcing their seats 50 against the conical portions 51 of the spindles 52 and 54, thereby connecting frictionally the reels to their respective spindles. Over the pivot pin 53' is drawn a sleeve 55, having teeth 56 upon its free-end, the said sleeve being fixedly attached to the pivot pin in any suitable manner. Upon the sleeve is coiled a spring 56', 100 one end of which bears against the lever 53, its other end being fastened to a post 57. This spring causes the supply reel to move toward the drum 42. A cap 58 coöperates with the sleeve 55, said cap being also provided with teeth, denoted by the numeral 59, said last named teeth being adapted to mesh with those of the said sleeve. The cap is held in engagement with the sleeve by a blade spring 60. The spindle 54 of the 110 wind-up reel is provided with a spur gear 61, meshing with the gear 48 upon the drum 42.

In placing the record tape upon the supply reel, the latter is swung around its pivot 115 pin 53' until the teeth of the sleeve 55 mesh with those of the cap 58, whereby the spindle 52 of the supply reel is held a suitable distance from the drum 42 against the action of the spring 56'. The supply reel is 120 then taken off its spindle, the record tape placed in position thereon, its free end wound around a portion of the drum 42 and attached to the wind-up reel 44. The supply reel is then swung back to its normal position. It is to be observed that the wind-up reel is arranged to be driven at a slightly higher speed than the surface speed of the drum, whereby an initial winding stress is introduced into the tape, tending to wind it 130

firmly upon the said drum, the latter acting to govern the speed of its travel. As the tape is being unwound from the supply reel, the latter is moved continuously by the 5 spring 56' toward the drum 42, thereby holding always the tape against the surface of the said drum.

The drum 42 and two reels are disposed horizontally, and at a suitable distance above 10 the said drum are located two slotted guides 62, extending in parallel relation to the longitudinal axis of said drum, and being attached in any suitable manner to the base plate of the casing 36. Into the slot of each 15 guide extends a sliding head 63, one carrying a stylus 64 hereinafter referred to as the "speed recording stylus" and the other one having attached thereto a stylus 65 herein-after termed the "load recording stylus." 20 Both styli are moved back and forth parallel to the longitudinal axis of the drum, their pencils or other marking devices being forced against the drum by springs 66. To the pencil holding tubes 67 of the styli are 25 attached short links 68, which are fulcrumed at 69 to arms 70. Each of these arms is provided with two rounded projections 71. The rounded projections of the arm of the speed recording stylus engage diametrically opposite portions of a face cam 73, which is rotatably mounted upon a stud 74, the latter being carried by a lever 75, that is fulcrumed at 76 to the base plate of the casing 36, a set screw 77 engaging a slot 78 in said lever and 30 serving to fix the position of the latter upon the said base plate. The arm 70 of the speed recording stylus is pivoted at 79 to a stem 80, having a reduced end 81 fitting into a bore 82 in the stud 74. The rounded projections 35 of the arm 70 are held in contact with the cam 73 by a spring 83, that is attached to the lever 75 and bears against the stem 80. The cam 73 is actuated from one of the front 40 wheels 84 of the truck. To this wheel is attached for this purpose a disk 85, having a cam 86, with which engages a lug 87, carrying a cam 88, with which engages a lug 87, carrying an anti-friction roller 88. The lug 87 is 45 formed upon a plunger 89, reciprocably disposed in a guide 90, the latter being preferably attached to the steering arm of the motor truck. The cam 86 is shaped in such a manner that the plunger will be moved back and forth, completing one cycle during each 50 revolution of the vehicle wheel. A spring 55 91, bearing against the guide 90 and an enlarged portion of the plunger 89, causes the anti-friction roller 88 to contact continuously with the cam 86. The movement of the plunger 89 may be transmitted to the cam 73 in the following manner: The last named 60 cam is provided with a worm gear 92, in mesh with a worm 93, which is suitably journaled in the casing 36 and has fixedly attached thereto an escapement wheel 94, actuated by a detent 95, that is pivoted at 96 to a

lug 97, the latter being formed upon the casing 36. The detent is fulcrumed at 98 to a plunger 99, projecting through a tubular extension 100 of the casing, said extension serving to guide the reciprocating motion of 70 said plunger. The plungers 89 and 99 are joined by a flexible connection, for instance by the tension member 101 of a Bowden type of flexible connecting means, the compression member 102 of the said connecting 75 means being attached to the guide 90 and to an externally screw threaded sleeve 103. The extension 100 of the casing 36 is also externally screw threaded. The threads of the extension 100 and of the sleeve 103 run in 80 opposite directions, and are engaged by a turn buckle 104 to permit of an adjustment of the length of the compression member 102 of the flexible connection. A spring 105 bears against the casing 36 and a collar 106 85 upon the plunger 99, carrying the last named plunger toward the cam 73 when the cable 101 is permitted to move toward the recording instrument.

As mentioned above, transversely the record tape 30 indicates two miles of travel of the vehicle, or in other words a movement of the speed recording stylus across the tape represents a distance of two miles. Inasmuch as the circumference of the vehicle 95 wheel is known, it is very easy to calculate the ratio between the worm 93 and the worm gear 92 to cause the latter to make one-half of a revolution for two miles travel of the vehicle. The distance between the 100 stud 74 and the longitudinal axis of the worm 93 is adjustable, the said stud being mounted upon the lever 75, thus permitting the cam 73 and the worm gear attached thereto to be replaced by a smaller or larger 105 one, as the size of the vehicle wheels may require.

The arm 70 of the load recording stylus is also provided, as above mentioned, with two rounded projections 71, engaging diametrically opposite portions of a face cam 107. This cam has a spindle 108 rotatably mounted in the base plate of the casing 36, the arm 70 being pivoted at 109 to a stem 110, the reduced end 111 of which fits into 115 a bore 112 in the spindle 108. The rounded projections of this arm are held in contact with the cam 107 by a spring 113, that is attached to the base plate of the casing 36 and bears against the stem 110. Upon the 120 cam is formed a spur gear 114, in mesh with a rack 115, that is secured to a sliding plunger 116, the latter projecting through a tubular extension 117 of the casing 36. A spring 118 is wound upon the plunger 116, 125 and bears against the casing and against a collar 119 upon the plunger 116, its purpose being to force the rack 115 upward. The plunger 116 is connected with the vehicle springs by a mechanism which transmits the 130

variations of the depressions of the springs to the said plunger, or in other words transmits the variations in the load on the vehicle. This transmitting mechanism comprises two 5 blade springs 120, one of which is attached to the forward axle of the vehicle by the usual spring clip 121, and the other one to the rear axle by the usual spring clip 122. These blade springs extend to the longitudinal 10 middle line of the vehicle, and have attached to their free ends a flexible cable 123, running over sheaves 124, that are carried by lugs 125 upon the bottom of the motor truck. The cable extends into a stationary 15 housing 126, that is secured in any suitable manner to the bottom of the motor truck, and has pivoted thereto at 127 a swinging lever 128, the free end of which is provided with a sheave 129. Two sheaves 130 are rotatably mounted in the housing 126; the 20 cable, passing into the housing from one of the blade springs 120, running partly over one of the sheaves 130, then extending toward and partly over the sheave 129, thence 25 back to and partly over the other sheave 130, and running then through the casing to the other blade spring 120. A spring 131, engaging the lever 128 and the housing 126, tends to force the sheave 129 away from the 30 sheaves 130. The lever 128 is provided with an arc-shaped slot 132, and in this slot are disposed clamping means 133 of a link 134, the other end of which is pivoted at 135 to a plunger 136. This plunger is joined by a 35 flexible connection with the plunger 116. This flexible connection may also be of the Bowden type, its tension member 137 being secured to the plungers 136 and 116. The compression member 138 of this connection 40 is adjustably secured to an extension 139 upon the housing 126 and to the tubular extension 117 upon the casing 36. The connection is made by turn buckles 140 and 141.

The slot 132 in the swinging lever 128 follows the arc of the circle, that is described by the outer end of the link 134 swinging around its pivot 135 when the vehicle carries no load at all. From this it appears that when the vehicle is empty, an adjustment of the outer end of the link 134 in the slot 132 does not produce a movement of the plunger 116, and, inasmuch as the full stroke of this plunger represents, as above mentioned, 160% of the load to be carried by 50 the vehicle, a position of the outer end of the link in the slot 132 is required that will produce a full traverse of the load recording stylus for the maximum, or 160%, load on any type of vehicle to which the load recording device is attached. In other words, the slot 132 is necessary in the lever 128 to permit of an initial setting of the moving parts of the load recording device when being attached to a vehicle.

The blade springs 120 must be strong and stiff enough to move the flexible cable 123 and the elements connected therewith without becoming deflected. Inasmuch as there is always a tension on the cable, the deflection of the springs will remain substantially 70 constant. The cable 123 connects, as is obvious from the foregoing, the two axles of the vehicle and will thus produce in the load recording stylus actuating mechanism a movement which is the average of the movements of the two ends of the vehicle body, so that an unequal loading of the vehicle at different times will not produce a different load record. The blade springs 120 may be anchored to diagonally opposite springs of 80 the vehicle, as shown in Fig. 22 of the drawings. This method of applying the blade springs produces an even more uniform record with unequal loading of the vehicle body. 85

The operation of this device is as follows: The record tape is applied to its carrying mechanism as above described. Inasmuch as the clock work is running continuously, it is obvious that, as long as or whenever the vehicle is at rest, a line parallel to the longitudinal lines 32 upon the record tape will be marked on the latter by the speed recording stylus. As soon as, however, the vehicle is started in motion, the cam 86 actuates the plunger 89 and thus the plunger 99. The latter operates the detent 95, which, in turn, engages the teeth of the escapement wheel 94 and moves the said wheel during each complete rotation of the cam 86 a distance 100 of one tooth. The worm 93 is thus accordingly moved step by step, imparting motion to the cam 73, whereby the speed recording stylus is moved across the record tape 30. The line drawn transversely of the tape 30 105 is inclined to the longitudinal lines 32, the degree of inclination, when read in conjunction with the transverse lines 31 upon the record tape, showing the speed of the vehicle. In this manner in the example shown 110 in Fig. 20 of the drawings, a permanent distance-, speed- and stoppage-diagram 142 is obtained, from which it appears that the vehicle started to move at 6 o'clock, going at a slow speed until 6.30; from 6.30 until 115 7.30 the vehicle was at rest, and from 7.30 until 8.15 in motion, and so on.

The operation of the load recording mechanism is as follows: The load recording stylus moves parallel to the longitudinal 120 lines 32 on the record tape whenever the load is constant. When there is no load on the vehicle, the load recording stylus rests on the marginal line 32 marked "0." If now a load is put on the vehicle, the vehicle 125 springs are compressed. This compression causes slack in the cable 123, which is, however, taken up by the spring 131, moving

the swinging lever 128 in the direction of the arrow shown in Fig. 15 of the drawings, and causing a corresponding movement of the link 134, and thus of the plunger 116. 5 This movement is transmitted to the cam 107 by the rack 115 and the gear 114 co-operating therewith, causing a partial rotation of the cam, which moves the load recording stylus a corresponding distance 10 transversely of the record tape. Obviously, if load is taken off the vehicle, the load recording stylus will move in the opposite direction. In this manner a load diagram 143 is obtained on the record tape, as shown 15 in Fig. 20 of the drawings, from which it appears that at 6.30 the loading was started and continued until 7.30, the load placed on the vehicle being 140%. From this point until 10.30 the load was constant, and from 20 10.30 until 11.00 some of the load was removed, bringing it down to 110%, and from there it was constant, etc. In connection with this diagram, it is to be noted that 100% means the normal capacity of the 25 truck, for instance five tons, and in this manner 160% would mean eight tons, and so on.

In the devices illustrated in Figs. 1 to 20, inclusive, the two recording styli are placed 30 as close together as the structure will permit; (in the case illustrated herein the distance between the two being somewhat exaggerated, the normal distance being about one-eighth of an inch). When therefore 35 the two diagrams are to be read conjointly, corresponding corrections will have to be made. If, however, the tape shown in Fig. 21 of the drawings is employed, wherein the load diagram and the speed diagram are 40 drawn side by side, the two styli could be placed in a line parallel to the axis of the drum 42, and in this case obviously no correction is needed.

The diagram 142 gives, as appears from 45 above, a distance, speed and stoppage record, when read in conjunction with the time graduations. The load record diagram, when read in connection with the time graduations, not only gives a record of the 50 load on the vehicle, but also the time consumed in loading and unloading. Inasmuch as both diagrams are reduced to a common scale, to wit: time, they are readable conjointly, that is to say with reference to Fig. 55 20, it will appear that, while the vehicle was at rest from 6.30 to 7.30, load was put on, the load remaining constant until 10.30. Examining, however, the speed diagram, we find that from 8.15 to 8.45 the vehicle was 60 stationary and the load constant, indicating thereby some irregularity on the part of the driver. Moreover, not only can the ton-hours and mile-hours be ascertained, but also the ton-miles, by reason of the above 65 referred to common scale. This common

scale, that is the time, thus forms the connecting link between the mile-hours and ton-hours, enabling the record to be reduced to ton-miles, that is to say to the desired standard of comparison of vehicle performance. 70

It is to be observed that, while herein a detailed description of the actuating mechanisms of the styli has been given, others may just as well be employed without departing from the invention, which lies mainly, as indicated above, in the provision of a record tape carrier that is operated by a clock mechanism and co-operates with two markers, one of which is actuated by one 75 of the wheels of the vehicle, and the other one by the depression of the vehicle body under the weight of the load thereon. The invention lies also in the method of producing two independent diagrams and reducing the same to a common scale so as to be readable either separately or conjointly, for the purpose set forth. 80 85

What I claim is:—

1. The combination with a vehicle body 90 and its carrying wheels, of a record tape having time, load and distance graduations, a clock mechanism for moving said tape, two markers, means actuated by the depression of the vehicle body under the weight of 95 the load for operating one of said markers to make a record of the load on said tape, and means actuated by one of the carrying wheels operating the other one of said markers for causing the same to make a 100 record on said tape of the movements of the vehicle.

2. The combination with a vehicle body 105 and its carrying wheels, of a record tape having time, load and distance graduations, a clock mechanism for moving said tape lengthwise, two markers mounted to move transversely on said tape, means actuated by the depression of the vehicle body under the weight of the load for operating one of said 110 markers to make a record of the load on said tape, and means actuated by one of the carrying wheels operating the other one of said markers for causing the same to make a record on said tape of the movements of 115 the vehicle.

3. The combination with a vehicle body 120 and its carrying wheels, of a record tape having time, load and distance graduations, a clock mechanism for moving said tape, two reciprocable markers, means actuated by the depression of the vehicle body under the weight of the load for operating one of 125 said markers to make a record of the load on said tape, and means actuated by one of the carrying wheels operating the other one of said markers for causing the same to make a record on said tape of the movements of the vehicle.

4. The combination with a vehicle body 130

and its carrying wheels, of a record tape having time, load and distance graduations, a clock mechanism for moving said tape lengthwise, two reciprocable markers mounted to move transversely on said tape, means actuated by the depression of the vehicle body under the weight of the load for operating one of said markers to make a record of the load on said tape, and means actuated by one of the carrying wheels operating the other one of said markers for causing the same to make a record on said tape of the movements of the vehicle.

5. The combination with a vehicle body and its carrying wheels, of a record tape having load and distance graduations and time graduations common to said load and distance graduations, a clock mechanism for moving said tape, two markers, means actuated by the depression of the vehicle body under the weight of the load for operating one of said markers to make a record of the load on said tape, and means actuated by one of the carrying wheels operating the other one of said markers for causing the same to make a record on said tape of the movements of the vehicle.

6. The combination with a vehicle body and its carrying wheels, of a record tape having load and distance graduations and time graduations common to said load and distance graduations, a clock mechanism for moving said tape, two reciprocable markers, means actuated by the depression of the vehicle body under the weight of the load for operating one of said markers to make a record of the load on said tape, and means actuated by one of the carrying wheels operating the other one of said markers for causing the same to make a record on said tape of the movements of the vehicle.

7. The combination with a vehicle body and its carrying wheels, of a record tape having load and distance graduations and time graduations common to said load and distance graduations, a clock mechanism for moving said tape lengthwise, two markers mounted to move transversely on said tape, means actuated by the depression of the vehicle body under the weight of the load for operating one of said markers to make a record of the load on said tape, and means actuated by one of the carrying wheels operating the other one of said markers for causing the same to make a record on said tape of the movements of the vehicle.

8. The combination with a vehicle body and its carrying wheels, of a record tape having load and distance graduations and time graduations common to said load and distance graduations, a clock mechanism for moving said tape lengthwise, two reciprocable markers mounted to move transversely on said tape, means actuated by the depression of the vehicle body under the weight of the load for operating one of said markers to make a record of the load on said tape, and means actuated by one of the carrying wheels operating the other one of said markers for causing the same to make a record on said tape of the movements of the vehicle.

the load for operating one of said markers to make a record of the load on said tape, and means actuated by one of the carrying wheels operating the other one of said markers for causing the same to make a record on said tape of the movements of the vehicle.

9. The combination with a vehicle body and its carrying wheels, of a record tape having time, load and distance graduations, a clock mechanism for moving said tape, two markers mounted to move in a straight line transversely on said tape, an arm attached to each marker, a cam coöperating with each arm, means actuated by the depression of the vehicle body under the weight of the load for actuating one of said cams, whereby its marker makes a record of the load on said tape, and means actuated by one of the carrying wheels operating the other one of said cams, whereby its marker is caused to make a record on said tape of the movements of the vehicle.

10. The combination with a vehicle body and its carrying wheels, of a record tape having time, load and distance graduations, a clock mechanism for moving said tape lengthwise, two markers mounted to move in a straight line transversely on said tape, an arm attached to each marker, a cam coöperating with each arm, means actuated by the depression of the vehicle body under the weight of the load for actuating one of said cams, whereby its marker makes a record of the load on said tape, and means actuated by one of the carrying wheels operating the other one of said cams, whereby its marker is caused to make a record on said tape of the movements of the vehicle.

11. The combination with a vehicle body and its carrying wheels, of a record tape having load and distance graduations and time graduations common to said load and distance graduations, a clock mechanism for moving said tape, two markers mounted to move in a straight line transversely on said tape, an arm attached to each marker, a cam coöperating with each arm, means actuated by the depression of the vehicle body under the weight of the load for actuating one of said cams, whereby its marker makes a record of the load on said tape, and means actuated by one of the carrying wheels operating the other one of said cams, whereby its marker is caused to make a record on said tape of the movements of the vehicle.

12. The combination with a vehicle body, of a record tape having time and load graduations, a clock mechanism for moving said tape, a marker, and means actuated by the depression of said vehicle body under the weight of the load for operating said marker to make a record of the load on said tape.

13. The combination with a vehicle body

- and its axles, of a record tape having time and load graduations, a clock mechanism for moving said tape, a marker, a flexible connection between the axles and body of the vehicle, and means inserted into said flexible connection actuated by the depression of the vehicle body under the weight of the load for operating said marker to make a record of the load on said tape.
14. The combination with a vehicle body and its axles, of a record tape having time and load graduations, a clock mechanism for moving said tape, a marker, a spring pressed lever oscillatably attached to said body carrying a sheave, a plurality of sheaves mounted upon said body, a flexible connection between the vehicle body and said axles extending over said sheaves, and a connection between said lever and said marker, whereby the latter is actuated by the depression of the vehicle body under the weight of the load to make a record of the load on said tape.
15. The combination with a vehicle body and its carrying wheels, of a record tape having time, load and distance graduations, a clock mechanism for moving said tape, and means for simultaneously producing a record on said tape of the weight of the load on said vehicle body and of the movements of the wheels.
16. The combination with a vehicle body and its carrying wheels, of a record tape having time, load and distance graduations, a clock mechanism for moving said tape, and means for simultaneously producing a record side by side on said tape of the weight of the load on said vehicle body and of the movements of the wheels.
17. The combination with a vehicle body and its carrying wheels, of a record tape having time, load and distance graduations, a clock mechanism for moving said tape, means actuated by the depression of the vehicle body under the weight of the load to make a record of the load on said tape, and means actuated by one of the carrying wheels to produce a record on said tape of the movement of the vehicle.
18. The combination with a vehicle body and its carrying wheels, of a record tape having time, load and distance graduations, a clock mechanism for moving said tape, means actuated by the depression of the vehicle body under the weight of the load to make a record of the load on said tape, and means actuated by one of the carrying wheels to produce a record on said tape of the movement of the vehicle, said last named two means operating simultaneously.
19. The combination with a vehicle body and its carrying wheels, of a record tape having time, load and distance graduations, a clock mechanism for moving said tape, means actuated by the depression of the

vehicle body under the weight of the load to make a record of the load on said tape, and means actuated by one of the carrying wheels to produce a record on said tape of the movement of the vehicle, said last named two means operating simultaneously and making side by side a record.

20. The combination with a vehicle body and its carrying wheels, of a record tape having load and distance graduations, means independent of the vehicle for moving said tape, and means for simultaneously producing a record on said tape of the weight of the load on said vehicle body and of the movements of the wheels.

21. The combination with a vehicle body and its carrying wheels, of a record tape having load and distance graduations, means independent of the wheels for moving said tape, and means for simultaneously producing a record side by side on said tape of the weight of the load on said vehicle body and of the movements of the wheels.

22. The combination with a vehicle body and its carrying wheels, of a record tape having load and distance graduations, a motor for moving said tape, means actuated by the depression of the vehicle body under the weight of the load to make a record of the load on said tape, and means actuated by one of the carrying wheels to produce a record on said tape of the movement of the vehicle.

23. The combination with a vehicle body and its carrying wheels, of a record tape having load and distance graduations, a motor for moving said tape, means actuated by the depression of the vehicle body under the weight of the load to make a record of the load on said tape, and means actuated by one of the carrying wheels to produce a record on said tape of the movement of the vehicle, said last named two means operating simultaneously.

24. The combination with a vehicle body and its carrying wheels, of a record tape having load and distance graduations, a motor for moving said tape, means actuated by the depression of the vehicle body under the weight of the load to make a record of the load on said tape, and means actuated by one of the carrying wheels to produce a record on said tape of the movement of the vehicle, said last named two means operating simultaneously and making side by side a record.

25. The method of obtaining a vehicle performance record, which consists in producing upon a clock mechanism driven tape a record of the weight of the load on the vehicle body and of the movements of the wheels thereof.

26. The method of obtaining a vehicle performance record, which consists in simultaneously producing upon a clock mech-

anism driven tape a record of the weight of the load on the vehicle body and of the movements of the wheels thereof.

27. The method of obtaining a vehicle performance record, which consists in producing upon a clock mechanism driven tape side by side a record of the weight of the load on the vehicle body and of the movements of the wheels thereof.
- 10 28. The method of obtaining a vehicle performance record, which consists in simultaneously producing upon a clock mechanism driven tape side by side a record of the weight of the load on the vehicle body and of the movements of the wheels thereof.
- 15

29. The method of obtaining a vehicle performance record, which consists in simultaneously producing upon a tape side by side a record of time, of the weight of the load on the vehicle body and of the movements of the wheels thereof during such time. 20

Signed at New York, in the county of New York, and State of New York, this 7th day of June, A. D. 1915.
